UNITED STATES PATENT OFFICE

CHARLES EVERETT BILLS, OF EVANSVILLE, INDIANA, ASSIGNOR TO MEAD JOHNSON & COMPANY, OF EVANSVILLE, INDIANA, A CORPORATION OF INDIANA

IRRADIATING APPARATUS

Application filed June 10, 1929. Serial No. 369,556.

This invention relates to irradiating apparatus and is particularly adapted for use in the irradiation of fluids and of substances carried in solution.

5 The main object of the invention is to provide apparatus simple in construction, in which the matter to be irradiated is exposed to light rays so as to receive the full benefit thereof in a very efficient manner and without exposure to air during the period of irradiation.

The apparatus has been used to advantage in the irradiation of solutions of ergosterol in arachis (peanut oil), but obviously other 15 edible oils, preferably bland vegetable oils, or other solvents may be used; and the invention is equally useful for irradiating oils and other fluids not containing added ergosterol.

20 It is old in the art to provide irradiating apparatus such as a quartz mercury vapor lamp and to locate the same in any desired position relative to a receptacle containing the substance to be treated. In using such 25 apparatus, the relative positions of the lamp and the receptacles are not always arranged to the best advantage for the intended purpose, and the treated substance may be exposed to air, which is to be avoided, especially in the case of oils which become rancid 30 when exposed to ultra-violet light and air.

One example of a type of lamp heretofore used for ultra-violet irradiation is that known as the Kromayer lamp, made by the 35 Hanovia Chemical and Manufacturing Company, which consists of a quartz burner containing the mercury and electrodes, a quartz jacket surrounding the burner but spaced therefrom to provide a vacuum chamber between the burner and the jacket, and an outer 40 casing of metal, having inlet and outlet ports. This outer casing is spaced from the quartz jacket and thus provides a chamber or passageway for water which is circulated through 45 the chamber for cooling the burner. Of course, the water does not touch the burner because it is separated therefrom by the quartz jacket and vacuum chamber. Heretofore such lamps have been placed in any 50 desired position relative to a receptacle con-

taining the substance to be irradiated, and the light rays from the burner pass through the quartz jacket, through the water used for cooling the lamp, and then through a window in the metal housing to the matter being 55 treated.

I have somewhat modified a lamp of this type to adapt it for use in the apparatus of the present invention, wherein the ergosterol-oil solution or other fluid to be irradiated is 60 caused to circulate through the lamp in order to receive the benefit of the ultra-violet light from the quartz burner in a most efficient and uniform manner, without exposure to air. The arrangement also obviates the necessity 65 for water cooling the lamp.

In the drawings:—

Figure 1 shows an elevation, partly in section, of the apparatus embodying my invention:

In that embodiment of the invention shown in the drawing, 5 is a support, such as a table, having mounted thereon a standard 6 which supports a reservoir 7 for containing the fluid to be treated. Above the reservoir 7 is a receptacle 8 containing a coil 9. The reservoir 7 has a cover 10 which may be removed when it is desired to fill the reservoir at the beginning of the process and there is an agitator 11 mounted in the cover 10 and depending therefrom into the reservoir. The agitator 11 is 70 operatively connected by gearing 12 and belt 13 with the shaft 14 of the motor 15, through speed reduction gearing (not shown) located 75 in the housing 16.

At the bottom of the reservoir 7 is an outlet port and conduit 17 leading to the pump 18, which is also operatively connected with the motor 15. 19 indicates an ordinary pressure gauge in a conduit 20 leading from the pump 90 and 21 is an adjustable by-pass inserted in the line of flow so that if the pressure should become too great the excess flow of liquid is returned to the reservoir 7 through the by-pass conduit 22.

The conduit 30 extends to the quartz mercury vapor lamp 23 which is tiltably mounted on any suitable support (not shown) by a movable joint 24. The quartz burner, indicated at 25, containing the mercury and elec- 100

trodes, is connected to a source of electrical current through the wires 26; the burner 25 being surrounded by a quartz jacket 27, spaced therefrom to form a vacuum chamber 5 between them. The outer casing 28, preferably made of metal, encloses the parts described and is spaced from the quartz wall 27 to form a chamber or passageway 29 surrounding said quartz jacket 27. The chamber 29 is provided with inlet and outlet ports, the conduit 20 being in communication with the chamber 29 through the inlet port and the conduit 30 being connected to the outlet port. The electrodes of the burner are imbedded in an oil-insoluble compound or cement, such as De Khotinsky cement, and only cork gaskets are used in order to adapt the lamp for having oily fluids circulated therethrough.

20 The conduit 30 extends from the outlet port of the lamp to the cooling coil 9 in the receptacle 8 and the coil 9 extends downwardly through the cover 10 of the reservoir. Water or other cooling medium is circulated through 25 the container 8 from the supply inlet 31 to the outlet conduit 32.

The reservoir 7 is also provided with an inlet conduit 33 through which an inert gas, such as carbon dioxide or nitrogen, may be introduced into the reservoir to occupy the space above the level of the fluid which is being treated. 34 indicates an outlet valve to drain the system.

The operation of the device is as follows:—

35 The ergosterol-oil solution or other fluid is placed in the reservoir 7, which is in communication with a supply of inert gas through conduit 33. The lamp 23 is supplied with current through the wires 26. It is necessary to 40 tilt a lamp of this type on the joint 24 in order to start it. The motor 15 is put into operation to actuate the pump 18 and the agitator 11, causing the fluid to pass at a predetermined speed of flow through the conduit 20 and into 45 the chamber 29 of the lamp. The rate of flow is regulated by the operation of the pump and pressure gauge so that the oil never gets hot as it passes through the chamber 29. When it has passed through the chamber 29 and out 50 into the conduit 30, it is only slightly warm and then it is cooled by passing through the coil 9. From there it is returned to the reservoir 7 and the operation is repeated.

The circulation of the oil solution is continued as long as is necessary to obtain good activation. For example, to activate two liters of a solution of ergosterol consisting of ten grams of ergosterol in two liters of arachis oil, using a modified Kromayer lamp at normal voltage, requires about three hours. However, the time of activation depends on many factors, such as voltage, age and condition of the lamp, concentration of the ergosterol solution, rate of circulation through 55 the lamp, purity of the solvent, etc.

From the foregoing it will be seen that the oil being circulated is at no time exposed to the deleterious effects of the air; all the fluid is uniformly treated with the light rays, and the full radiance of the lamp is utilized for its intended purpose. The circulation of the oily fluid through the lamp, as herein described, therefore results in unusually efficient and direct irradiation and obviates the necessity for water cooling the lamp.

70

75

I claim as my invention:—

1. Irradiating apparatus comprising a reservoir for the fluid to be treated, a quartz burner lamp having a casing, a burner, a chamber between the burner and the lamp casing, and inlet and outlet conduits between the lamp chamber and the reservoir, and means for repeatedly circulating the fluid through the lamp chamber.

80

2. Irradiating apparatus comprising a reservoir for the fluid to be treated, a quartz burner lamp having a casing, a burner, a chamber between the burner and the lamp casing, and inlet and outlet conduits between the lamp chamber and the reservoir, means for repeatedly circulating the fluid through the lamp chamber, and means for cooling the fluid after it has passed through the lamp chamber.

90

3. Irradiating apparatus comprising a reservoir for the fluid to be treated, an agitator in the reservoir, a quartz burner lamp having a casing, a burner, a chamber between the burner and the lamp casing, and inlet and outlet conduits between the lamp chamber and the reservoir, and means for repeatedly circulating the fluid through the lamp chamber, and for actuating the agitator.

95

4. Irradiating apparatus comprising a reservoir for the fluid to be treated, a quartz burner lamp having a casing, a burner, a chamber between the burner and the lamp casing, and inlet and outlet conduits between the lamp chamber and the reservoir, means for repeatedly circulating the fluid through the lamp chamber, and means for regulating the speed of flow.

100

5. Irradiating apparatus comprising a reservoir for the fluid to be treated, a quartz burner lamp having a casing, a burner, a chamber between the burner and the lamp casing, and inlet and outlet conduits between the lamp chamber and the reservoir, means for repeatedly circulating the fluid through the lamp chamber, and means for supplying inert gas to the reservoir above the level of the fluid.

110

6. Irradiating apparatus comprising a reservoir for the fluid to be treated, a quartz burner lamp having a casing, a burner, electrodes for the burner imbedded in oil-insoluble cement, a quartz jacket surrounding the burner but spaced therefrom, a chamber between the quartz jacket and the lamp casing, inlet and outlet conduits between the lamp chamber and the reservoir, and means for re-

115

peatedly circulating the fluid through the lamp chamber.

7. Irradiating apparatus comprising a reservoir for the fluid to be treated, a quartz burner lamp having a casing, a burner, electrodes for the burner imbedded in oil-insoluble cement, a quartz jacket surrounding the burner but spaced therefrom by a vacuum, a chamber between the quartz jacket and the lamp casing, inlet and outlet conduits between the lamp chamber and the reservoir, and means for repeatedly circulating the fluid through the lamp chamber.

8. Irradiating apparatus comprising a reservoir for the fluid to be treated, a quartz burner lamp having a casing, a burner, electrodes for the burner imbedded in oil-insoluble cement, a quartz jacket surrounding the burner but spaced therefrom, a chamber between the quartz jacket and the lamp casing, inlet and outlet conduits between the lamp chamber and the reservoir, means for repeatedly circulating the fluid through the lamp chamber, and means for cooling the fluid after it has passed through the lamp chamber.

9. Irradiating apparatus comprising a reservoir for the fluid to be treated, a quartz burner lamp having a casing, a burner, electrodes for the burner imbedded in oil-insoluble cement, a quartz jacket surrounding the burner but spaced therefrom by a vacuum, a chamber between the quartz jacket and the lamp casing, inlet and outlet conduits between the lamp chamber and the reservoir, means for repeatedly circulating the fluid through the lamp chamber, and means for cooling the fluid after it has passed through the lamp chamber.

10. Irradiating apparatus comprising a reservoir for the fluid to be treated, a quartz burner lamp having a casing, a burner, electrodes for the burner imbedded in oil-insoluble cement, a quartz jacket surrounding the burner but spaced therefrom, a chamber between the quartz jacket and the lamp casing, inlet and outlet conduits between the lamp chamber and the reservoir, means for repeatedly circulating the fluid through the lamp chamber, and means for supplying inert gas to the reservoir above the level of the fluid.

In testimony that I claim the foregoing as my invention, I affix my signature, this 28th day of May, 1929.

CHARLES EVERETT BILLS.
